Patented Oct. 7, 1913.

UNITED STATES PATENT OFFICE.

ROBERT L. COONEY, OF ATLANTA, GEORGIA.

STATIONARY FIRE-EXTINGUISHER SYSTEM.

1,075,017.

Specification of Letters Patent.

Patented Oct. 7, 1913.

Application filed November 29, 1909. Serial No. 530,470.

To all whom it may concern:

Be it known that I, ROBERT L. COONEY, a citizen of the United States, residing at Atlanta, in the county of Fulton and State 5 of Georgia, have invented new and useful Improvements in Stationary Fire-Extinguisher Systems, of which the following is a specification.

The present invention is an improvement 10 in stationary fire extinguisher systems and it involves certain novel features of construction, arrangement and operation whereby extreme simplicity and efficiency are attained as well as various other important 15 results and advantages to be hereinafter enumerated.

A preferred embodiment of the invention is illustrated by way of example in the accompanying drawings, wherein—

20 Figure 1 is a longitudinal sectional view of an apparatus constructed in accordance with the present invention. Fig. 2 is a detail longitudinal sectional view of the operating mechanism of the apparatus. 25 Fig. 3 is a detail sectional view of an alternative form of operating mechanism which has the same basic principles of construction and operation as that shown in Fig. 2.

Similar characters of reference designate 30 corresponding parts throughout the several views.

The system employed involves a stationary tank, as 1, which may contain a sufficient quantity of alkaline solution of desired strength and a distributing pipe, as 2, which has an extension, as 3, that projects to a point near the bottom of the tank 1.

The fire extinguisher agent supply means 40 involves a movable mechanical element for producing the operation thereof, and where the means is of the chemical mixing type, the movable mechanical element referred to may be constituted of the acid bottle, as shown. The acid bottle, indicated by the numeral 4, contains a charge of the acid which it is desired to employ and which, when mixed with the alkaline solution, causes the generation of a gas fatal to combustion, in the well-known manner. The bottle 4 is preferably of the inverting or overturning type and is pivotally supported on a bracket, as 4^a, by trunnions, as

4^b. The bottle 4 is normally sustained in a slightly inclined position in order that it may the more readily overturn at the proper time.

The operating mechanism by which the movement of the mechanical element, in this instance the overturning of the acid bottle, is produced, is confined wholly within the tank 1 and is of novel character, involving a latch which is related to the acid bottle in a novel manner and may be automatically operable by the automatic disturbance or creation of a pressure force at the time of the fire or which may be optionally operable by the manual operation of a part to produce the disturbance or creation of the pressure force.

The form of operating mechanism shown in Fig. 2, consists essentially of an axially movable piston which is disposed on an axis that is inclined with relation to the longitudinal axis of the tank. The piston, designated by the numeral 5, is movable within a co-axial cylinder 6 which has a lower portion 6^a of reduced diameter normally surrounding the piston and an upper portion 6^b of greater diameter for a purpose 80 which will presently appear. The piston 5 may be advantageously in the form of a hollow cylindrical shell, to secure the desired proportions and lightness of weight and its upper end projects slightly into 85 the cylinder portion 6^b while its lower end is provided with a co-axial stem, as 7, which projects loosely through an opening 8 in the cylinder portion 6^a and engages in a recess 9 which is preferably formed in 90 a lug or projection 10 that is provided on the bottle 4 at one side and preferably near the upper end thereof.

The cylinder 6 is preferably supported in the following manner. A gland or nut, as 11, is fitted in the distributing pipe within the tank and preferably in the union which connects the distributing pipe and its co-axial extension 3. A laterally projecting pipe or tube, as 12, is fitted in the bore of 100 the aforesaid gland or nut and for convenience of assemblage is horizontally positioned, being connected to the cylinder 6 by a union 13 and a pipe or tube section, as 14, the latter being co-axial with said cylinder, set into the upper head thereof and

in open communication therewith. Within the pipe 2 is a short length vertical pipe or tube, as 15, which is joined to the pipe or tube section 12 and which has its upper end turned laterally, as at 16.

The bottle 4 when released, overturns by gravity with the result stated, the developed high pressure forcing the contents of the tank through the system. The releasing of the bottle to accomplish the object stated is effected by retracting the piston and when the system is pressure controlled, *i. e.* normally charged with pressure, the retraction of the piston is effected automatically in a novel manner. The charging means, *e. g.* a pump or cylinder containing compressed air or gas, is advantageously connected to the distributing pipe and the pressure developed by the pump or issuing from the compressed air cylinder flows into the distributing pipe and into the tank, the piston the while assuming its lowermost position, as shown in Fig. 2, and maintaining the bottle in an upright position. A comparatively low degree of pressure is sufficient to produce the operations desired and the pressure in the pipe and in the tank will be kept equal, irrespective of their absolute degree, the pipe or tube 12 having for this purpose a nipple, as 17, with a pin hole or capillary bore affording communication between said pipe or tube and the tank.

Assuming that the system is charged with pressure, the automatic operation will be as follows. When a sprinkler head, distributing valve, or other equivalent device is opened, the pressure in the pipe 2 is suddenly and materially reduced as is also the pressure in the cylinder portion 6^b. The pressure in the tank is thus allowed to become operative, *i. e.* expand and the result of such expansion is that a column of liquid is forced through the extension 3 and for some distance up into the distributing pipe and that, after an almost infinitesimal period of delay following the inception of the movement of the liquid column, the pushing retraction of the piston commences, the piston then being moved simultaneously with the liquid column although, of course, at a slower rate of speed. It follows from the foregoing statements that at the time the operative movement of the piston is completed, the liquid column will be at a certain height in the pipe 2 and as this certain height at such time, can be computed with mathematical exactness, the pipe 15 aforesaid, is of such a length that its upper end is above the highest point of the liquid column at the time the piston has completed its operative movement. The developed high pressure holds the piston 5 against the upper head of the cylinder 6 and thus seals the opening of the pipe 14.

The advantages of the foregoing method of operation are that the outlet of the liquid is unobstructed by any movable parts; only a low degree of charging pressure is required; a simpler and less expensive operating mechanism may be employed; and leakages of pressure are without any effect in so far as any liability of premature operation is concerned. It is to be noted that the interval of time during which the water column is being raised and prior to the movement of the latch, is very slight. From actual experiments I should judge it was at the most, not over a fraction of a second.

Other methods of operation than that herein described may be employed. For instance, there may be no normal charging pressure in the distributing pipe or tank and the movement of the piston may be effected by creating a suction influence in the distributing pipe as in my copending application, Serial No. 519,420, or a compression influence in the tank as in my copending application Serial No. 530,468.

In Fig. 3, an alternative construction is shown, in which the cylinder and piston are vertically disposed, the former having its wall 6^a formed with an annular jacket 20, open at its upper end and the latter being of inverted cup shape and having its annular portion loosely fitting in the jacket 20. The jacket constitutes an efficient guide for the piston and is advantageously filled with oil or glycerin to prevent corrosion and reduce friction.

The operating mechanism disclosed has a number of novel advantages hereinafter more fully explained, among which are its non-interference with the flow of the solution through the distributing pipe, and the impossibility for deposit, if any there be, to prevent the operation of the piston. This last advantage is due to the construction of the piston and its adjuncts and to the fact that by extending the end of the piston into the chamber 6^b, should any deposit be present in the chamber which surrounds the piston the latter moves away from the deposit rather than into the same, as would be the case if a flat piston, resting on the bottom of the chamber 6^a were employed. Deposits are not liable to occur, however, since the operating mechanism is so arranged as to be disposed above the water line, since it is not in the path of the outgoing solution, since the bend 16 will ordinarily prevent solution or water from backing up in the pipe 15 after an operation of the system, and since, if for any reason this backing up of solution or water should take place, the solution or water thus backing up will be trapped in the chamber 6^b (when the piston has returned to its normal position) and will flow back into the tank through an opening, as 18, provided in the underside of

the chamber 6^b but will not find lodgment (at least to any material extent) in the space between the piston and the chamber 6^a.

A further advantage of the specific operating mechanism employed is that nothing short of a disturbance of pressure in the manner explained will produce an operative movement of the piston; consequently the operating mechanism will not be affected by any amount of jarring or by any rocking of the tank which, of course, would be incident to the use of the apparatus as a protection for sea-going vessels.

In order to drain off any excess solution that may be left in the tank after an operation of the system and which might otherwise interfere with the efficient recharging thereof with water and alkali, a cock, as 19, may be employed.

Having fully described my invention, I claim:

1. A stationary dry pipe fire extinguisher system including a tank and a distributing pipe communicating therewith, an overturning acid bottle in the tank, a piston cylinder in the tank and in communication with the distributing pipe, and a pressure operated piston movable in the cylinder and having means for latching engagement with the bottle.

2. A stationary dry pipe fire extinguisher system including a tank and a distributing pipe communicating therewith, a pipe or tube in the upper portion of the tank and also communicating with the distributing pipe, a piston cylinder connected to the end of the pipe or tube in the tank, an acid bottle pivotally mounted in the tank and a pressure operated piston fitted and movable in the cylinder and having means for latching engagement with the acid bottle.

3. A stationary dry pipe fire extinguisher system including a tank and a distributing pipe communicating therewith, a pipe or tube in the upper portion of the tank and also communicating with the distributing pipe, a piston cylinder connected to the end of the pipe or tube in the tank, a movable mechanical element in the tank and forming a part of fire extinguisher agent supply means and a pressure operated piston fitted and movable in the cylinder and having means for latching engagement with the element.

4. A stationary dry pipe fire extinguisher system including a tank, a distributing pipe communicating therewith, an acid bottle pivotally mounted in the tank, a pressure operated element in the tank having means for latching engagement with the acid bottle and a cylinder communicating with the distributing pipe and in which the element works.

5. A stationary dry pipe fire extinguisher system including a tank, a distributing pipe

communicating therewith, an acid bottle pivotally mounted in the tank and having a recess at one side thereof, a pressure operated latch within the tank for engagement in the recess to normally hold the acid bottle against overturning movement and a cylinder communicating with the distributing pipe and in which the latch works.

6. A stationary dry pipe fire extinguisher system comprising a tank having a distributing pipe, an acid bottle arranged to discharge its contents into the tank, a pressure operated piston for governing the discharging operation of the acid bottle, a piston cylinder, and a pipe communicating with the piston cylinder and with the distributing pipe, the piston cylinder being located outside of the distributing pipe, whereby the path of movement of the piston does not intersect the path of movement of the liquid flowing through the distributing pipe.

7. A stationary dry pipe fire extinguisher system comprising a tank having a distributing pipe, an acid bottle arranged to discharge its contents into the tank, a pressure operated piston for governing the discharging operation of the acid bottle, a piston cylinder and a pipe communicating with the piston cylinder and with the distributing pipe, the piston cylinder being located outside of the distributing pipe, whereby the path of movement of the piston does not intersect the path of movement of the liquid flowing through the distributing pipe, the tank and the pipe being adapted to contain elastic fluid under pressure, and the system having means to maintain the pressures in the pipe and the system at equal degrees and irrespective of leakage.

8. A stationary dry pipe fire extinguisher system including a tank, a distributing pipe leading therefrom, an acid bottle pivotally mounted in the tank, a part disposed in the tank and having latching engagement with the acid bottle to hold the same normally against overturning, means in communication with the distributing pipe by which an elastic fluid impulse may be transmitted and means susceptible to the action of the impulse being operable thereby to produce the withdrawal of the latching part from engagement with the acid bottle.

9. A stationary dry pipe fire extinguisher system including a tank, a distributing pipe leading therefrom, fire extinguisher agent supply means having a movable controlling element disposed in the tank, a part disposed in the tank and having latching engagement with the element to normally prevent the operation thereof, means in communication with the distributing pipe by which an elastic fluid impulse may be transmitted and means disposed in the tank and susceptible to the action of the impulse, being operable thereby to produce the with-

drawal of the latching part from engagement with the element.

10. In a dry pipe fire extinguisher system, a tank, a distributing pipe leading therefrom, the tank and the distributing pipe containing air and having a restricted communication to normally equalize the pressures, an acid bottle pivotally mounted in the tank, a piston latch engaged with the acid bottle to maintain the normal upright relation

thereof, and a cylinder communicating with the tank and in which the piston latch works.

In testimony whereof I, have hereunto set my hand in presence of two subscribing witnesses.

ROBERT L. COONEY.
